(57) **CLAIM**

We claim the ornamental design for a skin cleansing brush, as shown and described.

DESCRIPTION

FIG. 1 is an isometric view of a skin cleansing brush with a handle shown in dashed lines for environment.

FIG. 2 is a front isometric view of the skin cleansing brush of FIG. 1.

FIG. 3 is a rear isometric view of the skin cleansing brush of FIG. 1.

FIG. 4 is a front elevation view of the skin cleansing brush of FIG. 1.

FIG. 5 is a rear elevation view of the skin cleansing brush of FIG. 1.

FIG. 6 is a left side elevation view of the skin cleansing brush of FIG. 1.

FIG. 7 is a right side elevation view of the skin cleansing brush of FIG. 1; and,

FIG. 8 is a top plan view of the skin cleansing brush of FIG. 1.

The broken line showing of the handle in FIG. 1 illustrates environment and forms no part of the claimed design. All other broken lines illustrate unclaimed portions of the skin cleansing brush that form no part of the claimed design.
